ADJUSTABLE RING GAUGE

George Hohwart and Ernest F. Hohwart, Detroit,
Mich., assignors to N. A. Woodworth Company,
Ferndale, Mich., a corporation of Michigan

Application January 31, 1946, Serial No. 644,602

1 Claim. (Cl. 33—178)

1

This invention relates broadly to new and useful improvements in adjustable ring gages and more particularly to a gage of this type having novel means of adjusting the size of the gage body.

An important object of the present invention is to provide an adjustable ring gage that can be easily and accurately adjusted.

Another object of the invention is to provide novel adjusting means that is adaptable for either plain or thread ring gages.

Still another object of the invention is to provide a ring gage of the above-mentioned character in which the adjusting means applies a contracting force uniformly against the gage body and in such manner that the gaging bore maintains absolute circularity in all adjusted positions of the body.

Yet another object of the invention is to provide an adjustable ring gage of the above type that can be securely locked in any selected adjusted position.

Other objects and advantages of the invention will be apparent during the course of the following description.

In the drawings forming a part of this specification and wherein like numerals are employed to designate like parts throughout the same,

Fig. 1 is a side elevational view of an adjustable ring gage embodying the invention;

Fig. 2 is a transverse sectional view taken on the line 2—2 of Fig. 1;

Fig. 3 is a sectional view similar to Fig 2 but showing a modified form of the invention;

Fig. 4 is a side elevational view of still another form of the invention;

Fig. 5 is a transverse sectional view taken on the line 5—5 of Fig. 4; and

Fig. 6 is a transverse sectional view of still another form of the invention.

Attention is first directed to Figs. 1 and 2, which show one form of ring gage embodying the invention. The numeral 10 designates an annular gage member or body having a central gaging bore 12 which is adapted to receive and snugly fit a workpiece to be tested. In so far as the present invention is concerned, the member 10 may be adapted for testing either plain or threaded work; however, a thread ring gage is here shown by way of illustration, and the bore 12 is provided with internal screw threads 14.

In order that the member 10 be adjustable, it is provided with the usual radial locking slot 16 and adjusting slots 18. Locking slot 16 extends entirely through the member 10, and the adjusting slots 18 extend inwardly from the periphery but terminate short of the bore 12. As shown in Fig. 1, a number of adjusting slots 18 are provided, and they preferably are arranged in substantially equispaced relation around the member 10. These latter slots increase the

2

flexibility of the body member and assure more or less uniform expansion and contraction whereby to maintain absolute circularity of the bore 12 in all adjusted positions of the body.

Surrounding the body member 10 and spaced radially outwardly from the oppositely tapered, essentially flat, annular peripheral body surfaces 20 and 22 is an annular and rigid adjusting member 24. The latter preferably is of substantially the same width as the body 10 and is integrally attached to a clamping ring 26 which extends radially inwardly therefrom and is approximately one half as wide as the body. The inner annular surface 28 of ring 26 is tapered axially outwardly and snugly fits the body surface 20. Interposed between the other body surface 22 and the adjusting member 24 is a separate rigid clamping ring 30 which co-operates with the integral ring 26 to contract the gage body member 10. Ring 30 is provided with external screw threads 31 which engage the internal threads 32 of adjusting member 24, and its inner surface 34 is outwardly tapered to mate with the body surface 22. When the body 10 is fully expanded, the inner radial faces of locking rings 26 and 30 are spaced apart so that the latter can move axially for a limited distance.

In practice, the gaging bore 12 is made as large as the largest work to be tested, and the gage body 10 is adjusted to fit slightly smaller workpieces or to compensate for wear. To set the gage, a master thread gage plug having the same external diameter as the work to be tested is screwed into the bore 12, and the clamping ring 30 is tightened in the adjusting member 24 and against the body 10. As the locking ring 30 is moved axially inwardly by threads 31 and 32, it pulls the integral ring 26 solidly against the body surface 20 and presses its inner surface 34 solidly against the body surface 22. Pressure is thus applied simultaneously and equally against the surfaces 20 and 22 to effect a uniform contraction of the body 10.

Any suitable means can be used to rotate the locking ring 30. One means here shown by way of illustration merely comprises annular series of sockets 36 in the outer radial faces of the clamping rings 26 and 30, and, when this construction is employed, the only equipment required to set the gage is a couple of spanners having projecting lugs which fit in the sockets 36.

The usual procedure is to tighten clamping ring 30 until the body 10 is contracted sufficiently to prevent movement of the master plug. A tapered locking pin 40 is then driven into the locking slot 16 to expand the body. If desired, the walls of the slot may be provided with shallow, correspondingly tapered channels 38 which accommodate the pin 40. Pressure exerted by this pin against the walls of the slot 16 expands the

3

body 10 sufficiently so that the master plug can be turned with precisely the desired amount of resistance from the gage bore 12. Since locking pin 40 is driven forcibly into the slot 16, it is frictionally held in place by the walls of the slot. Also, expansion of the body 10 presses the peripheral surfaces 20 and 22 radially outwardly against the confronting and mating surfaces 28 and 34 so that it is substantially impossible to move any part of the gage until the locking pin 40 is removed.

Preferably, the locking slot 16 is provided with countersinks 42 which open through opposite sides of the body and radially relieve the terminal portions of locking pin 40. As a result, the expanding force exerted by pin 40 against the walls of the locking slot 16 is confined substantially to the middle of the body. This arrangement prevents, or at least inhibits, any tendency of the body to become distorted due to improper fits between the pin and the walls of locking slot 16.

The form of the invention shown in Fig. 3 is identical in construction and operation to the form hereinabove described, except that the clamping ring 26 is discrete and separate from the adjusting member 24. The internal screw thread 32 is extended entirely across the adjusting member to engage external screw threads 44 on the periphery of clamping ring 26. Thus, the ring 26 is movable independently of the adjusting member 24 and the companion clamping ring 30. In fact it is similar in all respects to the clamping ring 30 and is tightened simultaneously therewith to radially contract the body 10.

The form of the invention shown in Figs. 4 and 5 is identical to the form shown in Fig. 3, except that the threaded connections and beveled surfaces are transposed and the clamping rings 26 and 30 are split radially so that they are contractible to transmit thrust from the adjusting member 24 to the gage body 10. As best shown in Fig. 5, the body 10 is formed with a cylindrical, externally screw-threaded peripheral surface 46; and the clamping rings 26 and 30 are provided with annular screw-threaded inner surfaces 48 and 50. The clamping rings are screwed onto the gage body 10, as shown in Fig. 5, and have inwardly tapered, peripheral surfaces 52 and 54 which mate with correspondingly tapered inner surfaces 56 and 58 respectively on the adjusting member 24. As best shown in Fig. 4, the clamping rings 26 and 30 have radial through slots 60 which make them contractible and expansible. They are also provided with a plurality of radial adjusting slots 62 in the same manner as the gage body 10, which slots increase their flexibility and cause them to transmit radially compressive forces more or less uniformly against the body 10. While six adjusting slots 62 are here shown, it will be readily appreciated that any desired number may be provided. In general, the number of adjusting slots required to make the clamping rings sufficiently flexible varies according to the size of the rings and the materials from which they are made.

From the foregoing it will be apparent that, when they are tightened on the body 10 and against the tapered surfaces 56 and 58, clamping rings 26 and 30 are securely held in the selected adjusted position by the threaded connections with the body and pressure against surfaces 52 and 54 exerts a radial component of force which tends to contract the rings. Since the clamping rings snugly fit the gage body 10, they manifestly cannot contract without also contracting

4

the body. Thus, tightening of the clamping rings 26 and 30 contracts the gage body 10; and, conversely, loosening of the clamping rings permits the gage body to expand.

The form of the invention shown in Fig. 6 is identical to the form shown in Figs. 1 and 2, except that the clamping ring 26 comprises relatively thin, integrally connected, radial and axial annular flange portions 64 and 66 instead of the relatively massive and heavy piece of metal shown in Fig. 2. The radial flange portion 64 is integral with the adjusting member 24, and the axial flange portion 66 is outwardly tapered so that its inner surface 68 mates with and snugly fits the body surface 20.

Manifestly, the form of the invention shown in Fig. 6 operates in the same manner as the form shown in Figs. 1 and 2 to adjust the gage body 10. The main advantage of the latter form is that a substantial saving in weight is achieved without sacrificing strength or efficiency of operation. The larger size gages are quite heavy, and weight is an important factor, since they must be handled manually during testing of the workpieces.

It is to be understood that the forms of the invention herewith shown and described are to be taken as preferred examples of the same, and that various changes in the size, shape, and arrangement of parts may be resorted to without departing from the spirit of the invention or the scope of the appended claim.

Having thus described the invention, we claim:

An adjusting ring gage comprising a radially contractible gaging member having oppositely tapered peripheral surfaces; an adjusting member having a radial flange portion disposed around and at substantially the middle of said gaging member, axial annular portions extending in opposite directions from the radially inner and outer edges respectively of said radial flange portion, the inner axial portion having a tapered inner surface which mates and seats solidly against one tapered surface of the gaging member and the outer axial portion having an internally screw-threaded annular surface which surrounds and is spaced circumferentially from the other tapered surface of the gaging member; and a rigid clamping ring confined between the gaging member and the last-mentioned surface of the adjusting member, said ring provided with an inner tapered surface which mates and seats solidly against the confronting tapered surface of the gaging member and external screw threads which engage the internal screw threads of said adjusting member.
